NICHOLAS S. VEDDER, OF TROY, AND TOBIAS S. HEISTER, OF LANSINGBURG, NEW YORK, ASSIGNORS TO NICHOLAS S. VEDDER.

Design No. 3,330, dated January 5, 1869.

DESIGN FOR THE DOORS OF A STOVE.

The Schedule referred to in these Letters Patent and making part of the same.

To all whom it may concern:

Be it known that we, NICHOLAS S. VEDDER, of Troy, and TOBIAS S. HEISTER, of Lansingburg, in the county of Rensselaer, and State of New York, have jointly invented or produced a new and original Design for Stove-Doors, of which the following is a full and exact description, reference being had to the accompanying photographs, in which—

Figures 1 and 2 represent two stove-doors having our said new design.

Our new design for the door A consists of the compound central ornament *b c d e*, shaped and arranged on the rectangular panel *f*, and surrounded by the ornamental border-moulding *g*, so as to appear as shown in fig. 1; and

The design for the door H consists of the compound oval ornament *i j k l*, shaped and disposed on the panel *m*, with ornamental border-moulding *g*, so as to present the appearance represented in fig. 2.

What we claim as our invention or production, and desire to secure by Letters Patent, is—

The design for the stove-doors A and H, as herein shown and described.

In testimony whereof, we have hereunto subscribed our names, this 8th day of December, 1868.

NICHOLAS S. VEDDER.
TOBIAS S. HEISTER.
